UNITED STATES PATENT OFFICE

2,445,802

CONTAINER CLOSURE

Joseph Robinson, New York, N. Y.

Application January 8, 1945, Serial No. 571,748

1 Claim. (Cl. 220—46)

1

Wartime transportation of petroleum and petroleum products multiplied many times the number of closures normally used for closing the containers in which these products are shipped. This tremendous numerical increase, and the experience resulting from it, revealed faults not heretofore evident in existing closures. One of the closures most generally used (United States Patent No. 1,982,145) employs a square cross section gasket which can be used but once and which almost always twists when being applied in the field, especially in the theaters of war, where no application tools are available. Since no properly formed seat is provided in the closure to receive this gasket it is difficult to make the closure tight if its gasket is twisted. The result often is an imperfect joint through which dangerous and costly leakage occurs. "Breathing" (sucking in water from the drum head) is common to this type of closure for the reason that the sealing gasket, having no proper seat as aforesaid, is crushed imperfectly between the plug and the insert. Being a frail gasket (there is no room in this closure for a stronger size) its normal shape is thereby completely altered, resilience is deadened and deterioration of the gasket as a sealing agency is accelerated. A blow on the top of this closure tends to move the insert downward and loosen it in its housing in the drum head, further exposing the closure to "breathing." Shrinkage differentials between its housing and its insert are also frequent causes of leakage with this type of closure, particularly under the high temperatures encountered in desert warfare.

Among the objects of my invention are to so effectively minimize these faults as virtually to remove them; to provide a simple closure having a properly prepared seat for its gasket which preserves the gasket and insures a permanently tight gasket joint; to divide the direction of shrinkage of the closure insert in its housing so as to reduce the tendency of these parts to loosen under high temperatures; to swedge the insert and housing together in a manner which powerfully tightens the assembly and stiffens its resistance to blows, and to supplement this anchorage of the insert against rotation in the drum head with a secondary securing means consisting of a resilient device which serves also as a sealing ring. These and other novel features of my invention are described in the following specification, pointed out in the appended claim, and illustrated in the accompanying drawings in which

Figure 1 is a half vertical section and half ele-

2

vation of my improved closure showing the parts assembled and the seal cap in place;

Figure 2 is a vertical section through the housing A and the threaded insert C with the parts as they appear in one stage of assembly;

Figure 3 is a bottom view of the insert shown in Figure 2, and

Figure 4 is a sectional detail of an alternate assembling of the insert in the housing preparatory to thereafter forming the gasket seat 12.

My improvement comprises a slightly funnel shaped, cylindrical housing A of relatively shallow height suitably formed in the drum head B as by pressing. The housing is provided at its bottom with an annular seat 5 in which the flange 6 of the threaded bushing or insert C rests flush with the inner face of the drum head. The flange is flattened at 7 to fit against a correspondingly flat surface 8 in the housing to form a supplemental lock for holding the insert against rotation in the housing. The insert may be made of any desired material, but I at present press it from sheet metal of suitable thickness. Initially its walls 9 project vertically in a common plane throughout their length and at substantially a right angle to the flange 6, as indicated in dotted lines 10 in Figure 4. Either before the insert is threaded, or while it is being threaded, or after it has been threaded, its walls above the threads 11 are machined from the inside to approximately half their normal thickness. The thinned threadless portions of the walls is then spun or otherwise expanded laterally of the threads 11 to form the gasket seat 12, Figures 1 and 2. The resilient or pliable sealing ring and friction locking device 14, of suitable cross sectional size and shape, is passed over the top of the insert to the position shown in Figure 2, and the insert is placed in the housing A. A suitable die rolls the upper end of the insert over the top of the housing to form the lapped joint 15 shown in full lines in Figure 4 and in dotted lines in Figure 2. The same or another die causes the flaring walls of the housing to collapse and, together with the walls 9 of the insert C, to take, as the die strikes home, the final generally V-shaped assembled form, curved at 12—15, shown in Figure 1. Obviously this overlapped powerfully crimped interlock between the insert and the housing secures the parts against relative movement and flattens the sealing ring 14 to the shape shown in Figure 1. The resulting adhesion between the ring and the top of the flange 6, and between the ring and the adjacent wall of the housing A, is such as to form in itself a strong friction lock against rotation of the insert in the

housing, particularly if the ring 14 is dipped in a suitable cement before it is applied. Insertion of the bushing or insert C in the housing A, in preparation for this assembly, is eased by the flare or taper of the housing walls which also facilitates movement of the walls to the final collapsed generally V-shaped lapped joint formation illustrated in Figure 1. This formation shortens the vertical height of the insert C, throws its unthreaded upper portion into a plane at an abrupt angle to the vertical axis of the insert, and makes a compact sturdy closure having high resistance to vertical and lateral blows. The arrangement divides the direction of expansion of the insert so that approximately half thereof is vertical to the axis of the closure and half is at an angle thereto. The result is reduced tendency of the housing A and the insert C to move vertically relative to each other under desert temperatures. This collapsed V-shaped, tightly swedged lapped joint assembly, curved at 12-15, tightens, supplementarily to the sealing ring 14, against leakage and "breathing" through the joint between the insert C and the housing A and so firmly anchors the insert in the housing as to permit elimination, if desired, of the stops 7-8 in view particularly of the aforesaid strong friction lock between the insert and the housing formed by the powerfully compressed sealing anchor ring 14. A threaded plug D, Figure 1, die cast or otherwise formed of suitable material, and provided with a wrenching lug or lugs 16, is flanged at 17 to engage the top of the assembled insert C when screwed into the latter. The plug is provided with an annular seat 18 into which closely fits a pliable gasket 19, preferably round in cross section, and adapted to rest in its complementarily shaped laterally off-set seat 12 on the insert. A suitable seal-cap E is set over the assembled plug, and has its lower edge crimped under the shoulder 20 at the bottom of the lapped joint 15, Figure 1. The seal-cap serves to identify the contents of the drum and to prevent undislosed tampering therewith. The snug fit of the gasket 19 in its complementarily shaped seat 12-18 provides, when the gasket is compressed, a permanently tight, leak proof closure joint which will not "breathe"; which is not adversely affected by twists, few or many, in the gasket; which preserves the shape of the gasket, prolongs its life for repeated re-use, and makes removal of the plug D always easy by eliminating gasket "freezing" or fouling in the closure. With closures of the type shown in the aforesaid United States patent gasket "freezing" is a frequent occurrence, making plug removal difficult and requiring that heavy locking means be provided to prevent the insert from rotating in its housing when efforts are made to remove from it a gasket fouled plug.

The modification shown in Figure 4 consists in tightly pressing the insert C in the housing A of the drum head, fully compressing the sealing ring or friction lock 14, and rolling the upper end of the insert over the top of the housing before the gasket seat 12 is formed. The vertical walls 9 of the insert above the threads 11, and the adjacent walls of the housing, are then expanded outwardly to form the gasket seat, after which these walls are set to the final interlocked relation and shape shown in Figure 1. I am aware that to those skilled in the art other modifications may occur which do not depart from the spirit or scope of my invention, for which reason I desire not to be limited to the specific embodiments disclosed.

What I claim is:

In a closure for a container, in combination, an outwardly struck portion formed from the metal of the container to provide a downwardly facing shoulder and an outwardly extending tubular part of less diameter than said shoulder, a cylindrical spud disposed in said tubular part and provided at one end with an annular flange which seats against said shoulder, said spud having an outwardly extending sleeve which terminates beyond the outer end of said tubular part and having also an internally threaded portion which lies above the bottom of said flange and below the base of said outwardly extending sleeve, said sleeve above the threaded portion being off-set laterally outwardly to form an upwardly facing seat for a gasket and an outwardly opening peripheral groove within which the tubular part is received in V-shaped cross-section, the apex 35 portion of the V-shaped tubular part extending inwardly to a position beneath the gasket seat and into contact with the spud, the upper end of said sleeve being turned over the free end of said tubular part and sealed into liquid-tight rotationally immovable engagement therewith, a gasket on said seat, and a closure plug threaded into said spud into contact with said gasket.

JOSEPH ROBINSON.
